UNITED STATES PATENT OFFICE.

JOSEPH H. BAMBERG, OF TONAWANDA, NEW YORK, ASSIGNOR TO THE ALUMINUM CASTINGS COMPANY, OF CLEVELAND, OHIO, A CORPORATION OF OHIO.

PISTON FOR INTERNAL-COMBUSTION MOTORS.

1,329,821.

Specification of Letters Patent.

Patented Feb. 3, 1920.

Application filed June 28, 1916. Serial No. 106,513.

To all whom it may concern:

Be it known that I, JOSEPH H. BAMBERG, a citizen of the United States, residing at Tonawanda, in the county of Erie and State 5 of New York, have invented certain new and useful Improvements in and Relating to Pistons for Internal-Combustion Motors, of which the following is a specification.

This invention relates to pistons for use 10 particularly in internal combustion motors.

One of the objects of my invention is to produce a simple, light, durable and efficient skirted piston peculiarly adapted to meet the conditions which exist within an 15 internal combustion motor cylinder, including the stresses and strains imposed upon the piston, principally during the explosion stroke, and by the high heat generated at this time, which must be (a) efficiently and 20 economically utilized in the translation of heat into mechanical energy and (b) that not translated into mechanical energy properly dissipated.

My present invention also contemplates 25 an improvement in pistons of the general character disclosed in my Letters Patent 1,296,589.

It further contemplates improvements on the construction of piston disclosed in Letters Patent of the United States No. 30 1,092,870, to Edward O. Spillman and Louis P. Mooers by simplifying the construction and manufacture of pistons of this patented type through making them in two or more 35 parts, if desired of different materials, and of considerably lightening the construction as compared with the integral cast structure illustrated in the said patent.

Purely for the purposes of disclosure here- 40 in I have selected to illustrate and describe one construction of internal combustion motor, skirted piston embodying my improvement.

In the drawings, Figure 1 is a side eleva- 45 tion of a piston embodying my improvements.

Fig. 2 is a section on the line 2—2, Fig. 1.

Fig. 3 is a section on the line 3—3, Fig. 2.

Fig. 4 is a bottom or lower plan view.

50 Fig. 5 is a view partly in top or upper plan and partly in section.

1 is the skirt, body or guide portion of the piston, which may be made of cast iron or a section of steel tubing having diametrically

opposed apertures through it, 1^a, 1^b, con- 55 centric with the axis of the wrist pin 2, to permit the insertion and withdrawal of the latter as desired and the circulation of lubricant. If made of a section of steel tubing, the guide portion 1 may be drawn so 60 close in external diameter to the internal diameter of the cylinder walls with which it is adapted to co-act and co-operate, that it should not be necessary to machine this section or guide portion of the piston, al- 65 though it will be understood that if desired it may be machined or treated in any pre-furred mechanical manner.

3 indicates the head or top wall and connecting parts of the piston. It comprises, 70 preferably, an end wall 3', an annular outer wall 3^a preferably suitably grooved, as in- 75 dicated at 3^b, to receive suitable piston rings, and depending or inwardly turned connecting members 3^c, 3^d, connected with the end 75 wall 3' by an annular, inwardly extending wall or ribs 3^x. The portions 3' and 3^a of the piston may be made of an aluminum 80 alloy or any other suitable material. Their principal functions are to assist in translating the heat of the burning gases in the motor cylinder into mechanical energy, dis- 85 sperse a part of that heat and to carry the piston rings in such manner that they will co-act properly with the inner walls of the cylinder with which they are adapted to contact.

The skirt 1 is properly related to and connected with the head 3, preferably at the lower ends of the connecting members 3^c, 3^d. 90 These connecting members may be made in any suitable manner. Preferably I form the end wall 3', annular flanges or webs 3^a, 3^x, and connecting members 3^c, 3^d, integrally and of a metallic alloy having relatively 95 low specific gravity, as for example an aluminum alloy, the principal part of which is composed of the metal aluminum. The head and connecting parts of the piston may be cast or otherwise formed in any 100 suitable known manner. Preferably each of the connecting members 3^c, 3^d, carries intermediate its ends tubular wrist pin bosses 3^e, these two bosses being axially alined, in the well known manner to receive 105 a suitable wrist pin. One of them may have a depending lug or extension 3^f formed with a screw-threaded opening to receive a suit-

- able locking bolt or screw in a well known manner to secure in position the wrist pin to be mounted in the said boss.
- At its lower end each of the connecting members 3^c, 3^d preferably carries means for axially alining the head end 3' to the guide section 1 and connecting these parts rigidly together so that they will co-act properly within the motor cylinder. For the purpose I have illustrated the lower end of each of the connecting elements 3^c, 3^d, respectively, to be formed with a curvilinear wall 3^g carrying outwardly extending pads or spacing lugs 3^h and a cylindrical connector or rivet like extension 3^k. The outer surfaces of the spacing lugs or pads 3^h are suitably surfaced to engage the inner adjacent walls of the guide section 1 so as to space the guide section 1 and the connecting members 3^c, 3^d, properly relatively to each other and to insure the concentricity of the head 3' with the guide portion 1. Near its lower end the guide portion 1 may be formed with diametrically opposed apertures 1^c, 1^d, each of which is preferably counter-sunk or taper-turned or reamed as indicated, to receive the outer end of the adjacent connector lug 3^k, which is then upset in the well known manner within the counter-sunk walls of the adjacent openings 1^d so as to secure a simple, cheap, durable and positive connection between the body portion 1 of the piston and the connecting members 3^c, 3^d, respectively. Each connector member 3^c, 3^d, preferably has four spacing lugs 3^h which are arranged about the axis of the adjacent connecting lug 3^k in such manner that the engagement of their outer walls with the inner adjacent walls of the body section 1 serves to preclude relative movement of the connecting member and body portion 1 about the axis of the connecting lug 3^k.
- The upper end of the body portion 1 of the piston is separated from the adjacent lower wall of the annular outer wall 3^a of the piston head by an air gap at 4. The presence of this air gap tends to reduce to a minimum the transfer of heat from the piston head to the upper end of the skirt or guide portion 1 and further provides an avenue of escape inwardly for any excess oil or lubricant which may work its way up to this gap between the head and the skirt. It will be noted that any lubricant which enters the skirt either from the air gap 4 or through the openings 1^a, 1^b, may find a ready outlet as the skirt at its bottom is substantially open, there being substantially nothing on the inside of the skirt to retain lubricant within it.
- The disposition of the connecting members 3^c, 3^d, and web 3^x relative to the top or end wall 3' is such as materially to strengthen and support the top or end wall 65 3' near its center and where it is subjected to the greatest stresses at the time of the explosion within the motor cylinder. In fact, my improved piston is extremely rigid, rugged and durable. The head and connecting element 3 may be suitably ribbed or webbed between the inner surface of the end wall 3' and the adjacent wrist pin bosses, as indicated by the webs 3ⁿ, if desired. 75
- It will be understood that the sleeve or skirt 1 may be constructed so as snugly to fit the inner walls of the motor cylinder; whereas the head 3 may be given a considerable amount of clearance between its 80 peripheral wall 3^a and the inner wall of the cylinder, to allow for all necessary expansion of the head due to the high temperatures to which it is subjected. The heat transmitted to the head which is not translated into mechanical energy is transferred 85 downwardly by the connecting members 3^c, 3^d, to the lower end of the skirt, and much of it is given up to the surrounding air or vapor and thus dissipated so that the skirt 90 is kept relatively cool and may be readily lubricated to provide and maintain the proper working relationship between it and the inner wall of the motor cylinder. The fit between the skirt and the inner wall of 95 the cylinder, as before indicated, may be a snug sliding fit, and the area of the skirt which co-acts with the inner wall of the motor cylinder is such as to insure against slapping or rapping of the piston against 100 the inner wall of the cylinder. In fact the objectionable so-called piston slap, incident to the operation of numerous types of pistons for use in internal combustion motors, is eliminated by the use of a piston constructed in accordance with my invention. Furthermore, a piston embodying my improvements herein described practically 105 eliminates so-called "oil-pumping" or transfer of an undue amount of oil or lubricant 110 from the crank case to the upper end of the piston, resulting in undesirable smoking and undue and troublesome carbonization, among other things.
- Owing to the fact that the sleeve or skirt 115 is maintained relatively cool under all normal working conditions, the possibilities of scoring the inner walls of the cylinder are practically eliminated.
- Owing to the presence of the air gap or 120 air space 4 between the upper edge of the skirt or body section 1 and the lower edge of the annular portion 3^a of the piston head, the heat from the piston head will be transmitted inwardly and downwardly so that 125 such portion of it as does reach the skirt or body by conduction will do so at the lower end of the skirt and will not be suffi-

cient in amount to cause the necessary expansion of the skirt to effect binding between the skirt and inner walls of the cylinder or scoring.

5. It will be noted that my composite piston may be made relatively light in weight, which is of material advantage in assisting in reducing the weight of the reciprocating parts of the motor.

10. Pistons of my improved construction will be found to operate comparatively noiselessly, smoothly and efficiently.

To those skilled in the art many modifications of and widely differing embodiments 15 and applications of my invention will suggest themselves, without departing from the spirit and scope thereof. My disclosures and the descriptions herein are purely illustrative and are not intended to be in any 20 sense limiting.

What I claim is:

1. A piston for an internal combustion motor comprising a guide section separately formed and a head and connector section 25 formed integrally and comprising an end wall having an outer annular flange and a pair of inwardly extending connector members each formed intermediate its ends with a wrist pin boss and adjacent its lower end 30 with a plurality of outwardly extending projections, one of which is rigidly secured to the guide section near its lower end and another of which engages the inner wall of said guide section to insure axial alinement 35 of said sections.

2. A piston for an internal combustion motor comprising a guide section and a head and connector section, which are formed separately, said head and connector section being a casting and comprising an end wall having an outer flange and a pair of inwardly extending connector members each formed intermediate its ends with a wrist pin boss and adjacent its lower end with a 45 plurality of outwardly extending projections, one of which is rigidly secured to said guide section near its lower end and another of which is surfaced concentrically to said head and engages the inner wall of said guide section to position said sections concentrically.

50. 3. A piston for an internal combustion motor comprising a guide section and a head and connector section, said guide section being formed near its lower end with a pair of alined openings extending through the walls thereof, and said connector being formed with a pair of axially alined oppositely extending connector lugs each arranged to enter the adjacent one of said openings 55 through said guide section and to have its outer end upset against the walls of said opening.

4. A piston for an internal combustion motor comprising a guide section and a head 60 and connector section, said guide section be-

ing formed near its lower end with a pair of alined openings extending through the walls thereof, and said connector being formed with (1) a pair of axially alined oppositely extending connector lugs each arranged to enter the adjacent one of said openings through said guide section and to be secured to said guide section and (2) spacing lugs to position said sections concentrically.

5. A piston for an internal combustion motor comprising a guide section and a head and connector section, and said connector being formed at its lower end with (1) means to position said sections concentrically and (2) separate means for securing said sections together.

6. A composite piston comprising a tubular iron guide section having relatively thin walls, a combined piston head and connector element cast of a metallic alloy having a lower specific gravity than iron and comprising an end wall having an annular flange, the bottom of which is spaced from the upper end of said guide by an air gap, and a pair of inwardly extending connecting members, each having intermediate its ends a wrist pin boss which is axially alined with the wrist pin boss of the other and adjacent its lower end a plurality of spacing lugs disposed to engage the inner walls of said guide section adjacent the lower end thereof, and means for securing the lower end of each of said connecting members to the adjacent wall of said guide sections.

7. A composite piston comprising a tubular iron guide section having relatively thin walls, a combined piston head and connector element cast of a metallic alloy having a lower specific gravity than iron and comprising an end wall having an annular flange, the bottom of which is spaced from the upper end of said skirt by an air gap, and a pair of inwardly extending connecting members, each having intermediate its ends a wrist pin boss which is axially alined with the wrist pin boss of the other and adjacent its lower end a plurality of spacing lugs disposed to engage the inner walls of said guide section adjacent the lower end thereof, and means for securing the lower end of each of said connecting members to the adjacent wall of said guide section between the points at which said spacing lugs engage the inner wall of said guide section.

8. A piston comprising a head and connector portion integrally formed of metallic alloy having relatively low specific gravity, and comprising a top wall having an annular flange at its periphery and a pair of connector members extending inwardly from said end wall intermediate the center thereof and said annular flange, and each connector member having intermediate its

- ends a wrist pin boss axially alined with the wrist pin boss of the other and near its lower end spacing means having spacing surfaces concentric with the axis of 5 said head, a relatively thin walled tubular guide section having its upper end spaced from the lower end of said annular flange of the piston head to provide an air gap therebetween, the spacing surfaces of said 10 connecting members contacting with said guide section on its inner wall and near the lower end thereof, and means for securing said connecting members near their lower ends to the adjacent walls of said guide 15 section.
9. A piston comprising a head and connector portion integrally formed of metallic alloy having relatively low specific gravity, and comprising a top wall having an annular flange at its periphery and a pair of 20 connecting members extending downwardly from said end wall intermediate its center and said annular flange and each carrying intermediate its ends a wrist pin boss alined 25 with the wrist pin boss of the other, and having at its lower end an outwardly extending connecting lug, and a tubular relatively thin walled guide section disposed to have an air gap between its upper end wall and 30 the lower end wall of said annular section, and being formed adjacent its lower end with openings each to receive one of said connecting lugs on an adjacent connecting member and be connected by said lug to said 35 connecting member.
10. A piston comprising a head and connector portion integrally formed of metallic alloy having relatively low specific gravity, and comprising a top wall having an annular flange at its periphery and a pair of 40 connecting members extending downwardly from said end wall intermediate its center and said annular flange and each carrying intermediate its ends a wrist pin boss alined 45 with the wrist pin boss of the other, and having at its lower end an outwardly extending connecting lug, and a tubular relatively thin walled guide section disposed to have an air gap between its upper end wall and the lower end wall of said annular 50 section, and being formed adjacent its lower end with openings each to receive one of said connecting lugs on an adjacent connecting member and be connected by said lug to said connecting member, the walls of 55 said openings in said guide section being tapered and the outer ends of said connecting lugs being upset against said tapered walls.
11. A piston for an internal combustion motor comprising a guide section separately formed and a head and connector section formed integrally and comprising an end wall having an outer annular flange and a pair of inwardly extending connecting members each formed intermediate its ends with a wrist pin boss and adjacent its lower end with a plurality of spacing lugs disposed to engage the inner wall of said guide section adjacent the lower end thereof, and 60 means for securing the lower end of each of said connecting members to the adjacent wall of said guide section between the points at which said spacing lugs engage the inner wall of said guide section. 65
